[57] CLAIM

The ornamental design for a child's cloth comforter, as shown and described.

DESCRIPTION

FIG. 1 is a top perspective view of a child's cloth comforter showing our new design;

FIG. 2 is a bottom perspective view thereof;

FIG. 3 is a side elevational view thereof, the sides opposite and adjacent being identical in appearance;

FIG. 4 is a top perspective view of an alternative embodiment thereof;

FIG. 5 is a bottom perspective view of the embodiment of FIG. 4; and

FIG. 6 is a side elevational view of the embodiment of FIG. 4, the sides opposite and adjacent being identical in appearance.

Fig. 3
